UNITED STATES PATENT OFFICE.

GURDON G. WOLFE, OF PHILADELPHIA, PENNSYLVANIA, ASSIGNOR TO THE FOWLER & WOLFE MANUFACTURING COMPANY, OF PENNSYLVANIA.

DESIGN FOR A RADIATOR-SECTION.

SPECIFICATION forming part of Design No. 32,666, dated May 15, 1900.

Application filed April 16, 1900. Serial No. 13,146. Term of patent 14 years.

To all whom it may concern:

Be it known that I, GURDON G. WOLFE, of the city and county of Philadelphia, State of Pennsylvania, have invented a new and original Design for a Radiator-Section, of which the following is a specification.

My design is shown in the accompanying drawings, in which—

Figure 1 is a front elevation of a radiator-section embodying the design, and Fig. 2 is a transverse vertical section on the line $x-x'$ of Fig. 1.

The radiator-section is of flat hollow tubular form, composed of the outer tubular portions $a a b b$, the central hollow portion c , and the series of short tubular portions d and e between the central hollow portion and the outer tubes a and b .

s is a conventional surface ornamentation

on the outer tubes $a a b b$, and t is such ornamentation upon the central hollow portion c .

The essential feature of the design resides in the shape of the section formed of the outer tubular portions $a a b b$, the central hollow portion c , and the short connecting tubular portions d and e between the central portion c and the outer tubes a and b .

What I claim as new, and desire to secure by Letters Patent, is—

The design for a radiator-section substantially as described and as shown in the accompanying drawings.

In testimony of which invention I have hereunto set my hand.

GURDON G. WOLFE.

Witnesses:

FRANCES J. WOLFE,
JOSEPH THOMASSON.
